UNITED STATES PATENT OFFICE.

GOTTLIEB SCHNEIDER, OF BLUFFTON, INDIANA, ASSIGNOR TO THE RED CROSS MFG. CO., OF BLUFFTON, INDIANA.

SWINGING GUIDE FOR WINDMILL-PUMP RODS.

SPECIFICATION forming part of Letters Patent No. 742,911, dated November 3, 1903.

Application filed June 29, 1903. Serial No. 163,603. (No model.)

To all whom it may concern:

Be it known that I, GOTTLIEB SCHNEIDER, a citizen of the United States, residing at Bluffton, in the county of Wells and State of Indiana, have invented a new and useful Swinging Guide for Windmill Pump-Rods, of which the following is a specification.

My invention relates to guides for windmill pump-rods, and has for its objects to produce a device of this character of simple construction which will be efficient in operation and one which will move with the pump-rod, at the same time relieving the rod of the vibratory jerking motions with which it is usually attended.

To these ends the invention comprises the novel details of construction and combination of parts more fully hereinafter described.

In the accompanying drawings, Figure 1 is a top sectional plan of a portion of a windmill-tower having my device applied thereto. Fig. 2 is a perspective view, on an enlarged scale, of the device. Fig. 3 is a detail sectional view.

Referring to the drawings, 1, 1 indicate the upright standards of a windmill-tower, and 2 a horizontal brace-bar or girder extending between and bolted at its ends to a pair of the standards 1 as usual. These parts may be of any suitable or desired construction and material, inasmuch as they constitute no part of my invention.

3 is a block or member in the form of a casting having in its lower face a transversely-disposed recess 4, which receives the face of the girder 2, and in rear of the recess a horizontal perforated ear 5, while in advance of the recess there are a pair of spaced vertically-disposed lugs or ears 6, which carry an integral bolt or pintle 7, which is preferably cast in the ears during the process of casting the latter. The body of the casting is provided centrally of the space between the ears 6 with an opening 8, as shown, which is disposed in alignment with the openings 9 in ear 5, said openings being designed to receive the ends of a clip-bolt 10, which embraces the girder 2 and has nuts applied to its ends

above the casting, whereby the casting is securely attached to the girder.

11 is an arm pivoted upon the pintle 7 and consisting of a pair of side members 12, which are spaced at the pivotal end of the arm to lie one upon the outer face of each lug 6 and converge thence to a point of meeting adjacent to their outer ends, which latter are oppositely bent to form an open head 13, which embraces the pump-rod 14, a pivoting-bolt 15 being extended through the head and rod. The side members of the arm are at their point of meeting in rear of the head 13 united by rivets or otherwise.

In practice as the rod 14 is reciprocated vertically through the action of the wind-wheel mechanism the arm 11 will swing or play up and down on its pivot in a vertical plane, following the movement of the pump-rod, at the same time serving to guide the latter and relieve it of the vibratory and jerky motions usually attendant upon wind-wheel pump-rods when unguided.

From the foregoing it will be seen that I produce a device of simple construction which will be efficient in operation and one which may be readily and inexpensively applied for use. In attaining these ends I do not confine myself to the precise details herein set forth, inasmuch as minor changes may be made therein without departing from the spirit of my invention.

Having thus described my invention, what I claim is—

1. The combination with a frame and pump-rod, of a casting attached to the frame, and an arm pivoted to the casting and pump-rod and comprising a pair of members spaced at their pivotal end and converging toward their outer end, the outer ends of the members being oppositely bent to form an open head for the reception of the pump-rod.

2. The combination with a frame and pump-rod, of a casting attached to a member of the frame and having a recess to receive the latter, a clip-bolt extending through the casting and embracing the frame member, and an arm pivoted to the casting and to the pump-rod

and comprising a pair of members spaced at their pivotal end to receive the casting between them and converging toward their outer end, the outer ends of the members being oppositely bent to form an open head for the reception of the pump-rod.

5 In testimony that I claim the foregoing as

my own I have hereto affixed my signature in the presence of two witnesses.

GOTTLIEB SCHNEIDER.
